DESIGN FOR AN INDICATING INSTRUMENT

Henry Walter Mitchell, Chicago, Ill., assignor to
Emil A. Stromberg, Chicago, Ill.

Application September 5, 1935, Serial No. 58,446

Term of patent 14 years

To all whom it may concern:

Be it known that I, Henry Walter Mitchell, a citizen of the United States of America, and a resident of Chicago, Cook County, Illinois, have invented a new, original, and ornamental Design for an Indicating Instrument, of which the following is a specification, reference being had to the accompanying drawing, forming a part thereof.

Figure 1 is a perspective view of the indicating instrument showing my new design.

Figure 2 is an enlarged cross-sectional view taken on the line 2—2 of Figure 1.

I claim:

The ornamental design for an indicating instrument substantially as shown.

H. WALTER MITCHELL.
